UNITED STATES PATENT OFFICE

LEWIS DEGEN, OF BURLINGAME, CALIFORNIA

CODE REGISTER

Application filed May 21, 1929. Serial No. 364,719.

The present invention relates to a register such as is used in telegraphy for printing code characters. It is especially adaptable to fire alarm telegraphy wherein the signals in code are printed upon a strip of paper. The objects of this invention are to provide a register having any or all of the following features: means to print on a tape the code characters including an inked ribbon and type impression bar; novel means to operate the impression bar; and novel means to advance the inked ribbon.

An embodiment illustrative of the invention is shown in the accompanying drawings, in which:

Fig. 1 is a side elevation of a register with the operating parts within the casing shown in dotted lines; and Fig. 2 is an end elevation of the register.

Referring with more particularity to the drawing, a code register is shown adapted to be connected in the electrical sending circuit over which telegraphic impulses are sent. As is well known in fire alarm telegraphy, impulses are sent intermittently, the periods between impulses determining the code characters. The present invention relates to the printing mechanism, and only that portion of the register pertinent to the present invention is disclosed. The register comprises a casing 5 which houses a spring motor, not shown, except for a drive shaft for advancing the paper tape. This shaft is marked 6 and secured thereto is a toothed drive wheel 7.

Mounted upon the casing is a reel 8 for receiving a roll 9 of tape, a web being marked 10. The web is guided over an idler 11 along one side of the casing and over a shelf 12 supported by a suitable bracket 13. Mounted upon the side of the casing is a lever arm 14 carrying a pressure roller 15 which is urged toward the toothed roller 7 by means of a tension spring 16 secured at one end to the lever 14. The other end of the tension spring 45 is wrapped around an adjustment drum 17

so that by turning the drum, the tension upon the spring may be adjusted. The toothed wheel 7 is advanced intermittently by means of clock mechanism and thereby advances the web of paper. Secured to the casing and above the web of paper is a plate 18 having journaled thereon spools 19^a and 19^b. One spool serves as a take-up spool for an inked ribbon and the other as a feed spool, their functions being alternative so as to reverse the travel of the ribbon when the latter has been unwound from the spool serving as the feed spool. A ribbon 20 is passed downwardly over idlers 21 and 22 so that there is a bight of the ribbon passing parallel to the web. On the shaft 6 is a cam 23. Cam 23 has a high spot which engages a lever 24 pivoted on the casing and providing a cam follower having a post 25 with a roller at the upper end. The roller engages a lever 26 pivoted on plate 18 and having at the end a double pawl 27. The pawl has a slot in which is disposed a pin 28 mounted on an arm 29 secured to a shaft 30 so that by swinging the arm to one side or the other, the pawl 27 may be disposed to engage either a ratchet wheel on spool 19^a or a ratchet wheel on spool 19^b. Rotation of the toothed wheel 7 will cause the follower to be lifted and the pawl to be advanced, thereby turning the spool 75 with whose ratchet wheel the pawl is engaged.

Secured to the plate 18 is an anvil 31 having a type member provided on its face opposing the ribbon with a type character such as may be suitable for impression upon the strip of paper. Pivotedly mounted upon the casing 5 at 32 is an impression bar 33 having a platen head 34 opposed to the type member and between which and the type member the ribbon and strip of paper passes. Impression arm 33 is fixed to a shaft which is journaled in the casing and secured to the shaft is a tappet arm 35. A tension spring 36 tends to hold the impression bar with the platen against 90

the strip of paper. An armature lever 37 is pivoted at 38 to coact with electromagnets 39 which are energized by the electrical impulses. A screw member 40 is secured to the armature lever at its free end and has a finger serving as a tappet finger to engage the arm 35. The arrangement is such that the tappet finger may be adjusted with respect to the tappet arm. The tappet finger and tappet arm constitute a negative tappet device which when the electromagnets are energized pull the armature downwardly and cause the impression arm to be moved downwardly away from the paper, the spring 36 returning the impression arm so as to strike the paper and cause an impression to be made by the type member 31. A limit post 41 acts as a stop for the upward movement of the armature lever, while an abutment 42 engaging a threaded pin 43 mounted in a post 44 on the casing determines the extreme upper position of the impression lever. The latter adjustment provides for adjusting the magnitude of the impact of the platen.

As the electrical impulses are received, the clockwork is set in motion to cause the toothed drive wheel 7 to rotate advancing the paper. The cam 6 causes the pawl to intermittently rotate the take-up spool and move the inked ribbon. At each impulse, the armature lever 37 is drawn toward the electromagnets 39 and through the tappet device the impression lever is swung to retracted position.

What I claim is:—

1. A telegraphic register comprising a frame, an electromagnet for energization by electric impulses, a pivoted armature lever for said electromagnet, an impression bar pivotally mounted on said frame and having an impact head, a negative tappet device disposed between said armature lever and impression bar for operation of the latter by said armature lever, spring means connected to said impression bar to cause said impression bar to strike a paper tape, means for advancing a paper tape across said impact head, an anvil opposed to said impact head and between which the paper tape to receive impressions passes, ribbon feed and take-up spools, an inked ribbon on said spools passed between said anvil and impact head, there being a type character between said anvil and head, and means to rotate said spools and advance said ribbon.

2. A telegraphic register comprising a frame, an electromagnet for energization by electric impulses, a pivoted armature lever for said electromagnet, an impression bar pivotally mounted on said frame and having an impact head, a shaft fixed to said impression bar and having a tappet arm, a tappet finger on said armature lever to engage said arm and cause retraction of said impression bar, means for advancing a paper tape across said impact head, an anvil opposed to said impact head and between which the paper tape to re-

ceive impressions passes, a spring connected to said impression bar to restore said bar and cause said impact head to strike said paper tape, ribbon feed and take-up spools, an inked ribbon on said spools passed between said anvil and impact head, there being a type character between said anvil and impact head, and means to rotate said spools and advance said ribbon.

3. A telegraphic register comprising a frame, an electromagnet for energization by electric impulses, a pivoted armature lever for said electromagnet, an impression bar pivotally mounted on said frame and having an impact head, a tappet device disposed between said armature lever and impression bar for operation of the latter by said armature lever to cause retraction of said impression bar, said tappet device being disposed to amplify the motion between said armature lever and said impression bar, means for advancing a paper tape across said impact head, an anvil opposed to said impact head and between which the paper tape to receive impressions passes, a spring connected to said impression bar to restore said bar and cause said impact head to strike said paper tape, ribbon feed and take-up spools, an inked ribbon on said spools passed between said anvil and impact head, there being a type character between said anvil and impact head, and means to rotate said spools and advance said ribbon.

4. A telegraphic register comprising a frame, an electromagnet for energization by electric impulses, a pivoted armature lever for said electromagnet, an impression bar pivotally mounted on said frame and having an impact head, a shaft fixed to said impression bar and having a tappet arm, a tappet finger on said armature lever to engage said arm and cause retraction of said impression bar, said tappet arm and tappet finger being disposed to amplify the motion between said armature lever and said type bar, means for advancing a paper tape across said impact head, an anvil opposed to said impact head and between which the paper tape to receive impressions passes, a spring connected to said impression bar to restore said bar and cause said impact head to strike said paper tape, ribbon feed and take-up spools, an inked ribbon on said spools passed between said anvil and impact head, there being a type character between said anvil and impact head, and means to rotate said spools and advance said ribbon.

5. A telegraphic register comprising a frame, an electromagnet for energization by electric impulses, a pivoted armature lever for said electromagnet, an impression bar pivotally mounted on said frame and having a platen head, a negative tappet device disposed between said armature lever and impression bar for operation of the latter by said armature lever, spring means connected

to said impression bar to cause said bar to strike a paper tape, means for advancing a paper tape across said platen head, an anvil carrying a type character opposed to said platen head and between which the paper tape to receive impressions passes, ribbon feed and take-up spools, an inked ribbon on said spools passed between said anvil and platen head, and means to rotate said spools and advance said ribbon.

10 In witness that I claim the foregoing I have hereunto subscribed my name this 9th day of May, 1929.
